TRANSMITTING TUBE FOR SUBMARINES AND LIKE VESSELS

Filed Feb. 23, 1928

UNITED STATES PATENT OFFICE

CHARLES A. OHMAN AND WILLIARD T. OHMAN, OF GREAT KILLS, NEW YORK

TRANSMITTING TUBE FOR SUBMARINES AND LIKE VESSELS

Application filed February 23, 1928. Serial No. 256,151.

This invention relates primarily to the hull or wall structure of a submarine, ship or other vessel of any kind or class and particularly to the provision of a tube for transmitting various substances, food or other elements through the hull or wall structure, and including an apparatus or mechanism employed in conjunction with such tube structure to facilitate the transmission of the products in question; and the object of the invention consisting in providing the hull or wall structure of vessels of the class described with an attachment or with a built in structure including one or a plurality of tubes, placing one or more compartments within the vessel in communication with the exterior of the vessel, means being employed for sealing and enclosing the inner and outer ends of said tubes when not in use; a further object of the invention being to provide means for coupling a plurality of flexible tubes with the outer or exterior ends of the tubes of said vessel, and for bracing said flexible tubes where coupled, to relieve stress or strain thereon to which the same may be subjected; a further object being to provide means for draining the transmission tubes when the flexible tubes have been coupled therewith and prior to the operation of transmitting products or elements therethrough and into the compartment or compartments of the vessel; a further object being to provide means whereby signals may be transmitted through the hull or wall of the vessel to one of the compartments therein to control and regulate the use and operation of the transmitting mechanism or apparatus employed; and with these and other objects in view, the invention consists in an apparatus of the class and for the purpose specified which is simple in construction, efficient in use, and which is constructed as hereinafter described and claimed.

The invention is fully disclosed in the following specification, of which the accompanying drawing forms a part, in which the separate parts of our improvement are designated by suitable reference characters in each of the views, and in which:

Fig. 1 is a sectional view of a part of a

hull of a vessel, showing one method of carrying our invention into effect, and indicating the method of its use.

Fig. 2 is an outside view of the hull as seen in Fig. 1 of the drawing.

Fig. 3 is an outside view of the hull showing the closure plate attached prior to the application of the structure seen in Figs. 1 and 2.

Fig. 4 is an inside view of the structure seen in Fig. 1.

Fig. 5 is a detail view of one of a number of the tubes shown in Figs. 1 and 2 of the drawing; and,

Fig. 6 is a view similar to Fig. 1, showing a modification and also eliminating part of the structure shown in Fig. 1.

In submarines and like vessels when submerged in a body of water or the like, such for example, in sunken vessels it has been heretofore impossible to provide a quick, accessible and practical means for transmitting various substances or elements from a source of supply to one or more compartments of the vessel or ship. It is the object of our invention to provide the hull or wall structure, oftentimes referred to, as the bulkhead, with one or more tubes or passages arranged in one of a multiplicity of sections spaced throughout the bulkhead and opening into one or more compartments or chambers within the ship or vessel so that air, heat, food, light and other elements or products may be transmitted from a source of supply through the bulkhead to such room or chamber, or one of a number of rooms or chambers within the vessel, and further to provide for the circulation of air for the purpose of maintaining or saving the lives of those within such room or compartment of a sunken vessel, until such time as the vessel may be raised or salvaged.

In carrying our invention into effect, we have shown in Figs. 1 to 5 inclusive, one form of construction wherein 10 represents the outer wall or bulkhead of a submarine or other vessel and 11 the inner wall. As seen in Fig. 1 of the drawing, these walls are joined by a housing or casing structure 12 formed integral or coupled with the walls 100

10 and 11 in any desired manner, the structure being shown integral in the accompanying drawing. At this time, it is to be understood that one or more of the casings 12 may be employed at spaced intervals about the hull or bulkhead of the vessel and opening into different chambers or compartments therein.

The casing 12 includes an outer transverse wall member 13 and an inner transverse wall member 14. These wall members are joined by integral tubular bodies 15, 16, 17, 18 and 19, the bodies 18 and 19 being shown in Fig. 2 of the drawing, while the others are illustrated in Fig. 1. These bodies are all of substantially the same construction and the outer ends thereof are externally threaded as seen at 20, Fig. 5 of the drawing, in which figure, one of the tubes is shown in section. The externally threaded extensions of said tubes are contained within a chamber 21 formed within the casing 12 outwardly of the wall 13, and the tubes are arranged in a circumferential path about what might be termed the axis or central portion of the casing.

A ring or eye 22 is secured to the wall 13 centrally thereof and is mounted within the chamber 21, and is used for the purpose of coupling a guide rope, or coupled therewith in the use of the apparatus as later described. Another chamber 23 is formed inwardly of the wall 14 which opens into a room or compartment within the vessel to give access to the inner ends of the tubes 15 to 19 inclusive. The inner ends of the tubes 15, 17, 18 and 19 or the ends contained within the chamber 23 are each provided with valves 24 to control the communication through the passages in said tubes, while the tube 16 is of special construction and is adapted for use as a signal tube, utilizing an electric light bulb or bulbs for transmitting signals. This tube is provided at its inner end with a closure cap 25 supporting a lens 26 which closes the inner end of the tube and through which signal lights may be seen as later described. This tube is also preferably provided with a drain cock 27 to drain off water which may collect in the tube in the use of the apparatus.

The chamber 23 is normally closed by a cover plate 28 mounted upon studs 29 in the inner wall 11 of the bulkhead, which studs are engaged by nuts 30 rotatably mounted in and carried by the cover 28, said cover preferably seating on a gasket 31 to insure a water and air-tight connection between the parts. The cover 28 is also provided with a drain cock 32 for relieving air pressure or water that may be contained within the chamber 23 in the use of the apparatus and is also provided with a transparent panel or sight 33 arranged in alignment with the lens 26 at the end of the tube 16.

The outer chamber 21 is normally closed

by a plate or cover which is shown at 34 in Fig. 3 of the drawing, said cover carrying nuts 35 similar to the nuts 30 engaging studs 36 on the outer wall 10 of the bulkhead. The cover 34 is provided with a plug 37 having an angular socket 37a to receive a suitable wrench whereby the plug may be removed to close the pressure on both sides of the cover to facilitate the removal thereof in putting the transmitting properties into use.

We also employ in conjunction with the casing 12 and the several tubes thereof, a plurality of flexible tubes which lead from a source of supply and which are adapted to be coupled with the tubes 15 to 19 inclusive as a unit. In practice, we provide a coupling member 38 in the form of a ring-like body having a plurality of depending circumferentially spaced arms 39 forming therebetween, apertures 40, and the ends of the arms 39 are joined by an annular ring or flange 41 carrying at spaced intervals, nuts 42 which are adapted to be mounted upon the studs 36 after the cover 34 has been removed in the manner indicated in Figs. 1 and 2 of the drawing.

A plurality of coupling members 43, all of the same construction, are spaced circumferentially of the ring 38 and rest in seats or bearings formed in said ring and in such manner as to be in proper axial alignment with the tubes 15 to 19 inclusive. These couplings are held in place by arc-shaped straps 44 as clearly seen in Figs. 1 and 2. The flexible tubes 45 for placing the tubes 15 to 19 inclusive in communication with a source of supply or atmosphere are secured to the couplings 43 in any desired manner as seen at 46. The ends of the couplings 43 are provided with coupling nuts 47 adapted to be threaded upon the external threads of the tubes 15 to 19 inclusive, and a suitable packing 48 is preferably carried by the couplings 43 to insure a seal in the joint between the couplings and said tubes.

The coupling 43 to be coupled with the tube 16 differs from other couplings in that the same includes a projecting pipe 49 provided at its outer end with a lens 50. In said pipe and insulated therefrom by insulation 51 are two circuit wires 52 and 53 which wires are coupled or placed in circuit with each of three electric bulbs 54, 55 and 56 arranged in a chamber at the other end of the pipe 49 so that said bulbs may be visible through the lens 50, and lens 26, as well as the transparent panel or side 33.

In Figs. 1 to 5 inclusive, we have shown the apparatus as applied to what might be termed a double wall hull or bulkhead. In Fig. 6 of the drawing, we have shown a modification wherein a single wall bulkhead 57 is employed. This bulkhead is set inwardly where our improved apparatus is to be located as shown at 58 to form a chamber 59 outwardly of the portion 58 of the bulkhead, which is

closed by a cover 60 similar to the cover 34, said cover having nuts 61 engaging studs 62 on the bulkhead. The studs 62 are the same as the studs 36. In the construction shown in Fig. 6, the wall 57 or the offset portion 58 thereof is preferably provided with circumferentially spaced bushings 63 in which pipes or tubes 64 are mounted and secured. The pipes 64 are of the same construction at their end portions as the tubes 15 to 19 inclusive and are so arranged as to receive the couplings 43 shown in Figs. 1 and 2 of the drawing.

The pipes 64 are externally threaded to receive clamp nuts 65 and 66 arranged at the outer and inner ends of said pipes and cooperating with the corresponding ends of the bushings 63 to form water and air tight seals between the pipes and said bushings. If desired, suitable packings may be employed.

With the construction shown in Fig. 6, it will be understood that the pipes extend into a chamber or compartment of a ship, and the inner ends of said pipes are normally closed by a cover 67 which is cup-shaped in form and provided with a peripheral flange 68 in which is mounted a plurality of nuts 69 coupled with the inner ends of the studs 62. It will also be noted that an anchor ring 70 similar to the ring 22 is secured centrally of the wall 58 and is arranged within the chamber 59.

In the use of our invention as illustrated in both forms of construction shown, it will be understood that the covers 28 and 34 as well as the covers 60 and 67 are mounted in position to form closures for the chambers and tubes of my apparatus. The outer covers 34 and 60 are of such structure as to not materially interfere with the purpose of the vessel through the water or to offer any resistance which would be detrimental. In the event of the sinking of a ship or vessel through accident or otherwise, and especially in the case of the sinking of submarines where the seamen are confined in one or more rooms or compartments of the vessel, the lives of the seamen so trapped or confined may be saved while the salvaging of the ship takes place.

In the first step in putting our apparatus into operation, a diver descends to the ship and removes the nuts 35, retaining the cover 34 in place, and also removes the plug 37 to facilitate the removal of the cover from the studs 36 by equalizing the pressure on both sides of the cover. It is preferred that a cable or other guide strand taken down by the diver be coupled with the ring 22 in order to facilitate the further steps necessary to accomplish the desired result. The cable in question is indicated by the dotted lines at 71 in Fig. 1 of the drawing, and this cable may serve as a guide member for sending down to the diver the unit consisting of the rings 38-41 with the couplings 43 mounted therein and the pipes or tubes 45 coupled therewith. When

this unit reaches the desired position on the hull of the vessel where the cover 34 has been removed, the ring 41 is placed in position upon the studs 36 and the ends 42 are threaded onto said studs to secure said ring, the arms 39 and ring 38 which may be termed a frame, in position. When properly placed and secured in position, the couplings 43 will be arranged in axial alinement with the tubes 15 to 19 inclusive, and the couplings 47 will then be threaded onto the threaded ends 20 of said tubes by a suitable wrench operated through the apertures 40 between the ribs 39, it being understood that the valves 24 on the inner ends of the tubes 15, 17, 18 and 19 are closed while the inner end of the tube 16 is closed by the lens and cap employed.

In lowering the coupling unit through the water prior to securing the same in position as above stated, compressed air may be pumped through the several tubes 45 with the exception of the tube carrying the electric wires, the latter being normally sealed in order to prevent water from entering said tubes in this operation. On the other hand, said tubes may be lowered, allowing the water to pass therethrough, and after the connection has been completed with the several tubes 15 to 19 inclusive, the tubes 45 may be pumped out to remove the water therefrom, from the deck of a salvaging vessel. When this operation is completed, the signal will be transmitted to those within the compartment of the ship with which the chamber 23 communicates by the flickering or flashing of one or two of the bulbs 54, 55 and 56 to send a code or other message notifying those within the compartment that the coupling has been made. The valve 32 on the cover 28 will then be opened to test whether or not any leak exists in the various couplings of the pipes, this being a matter of safety, and if no leak occurs, the cover 28 is then removed by loosening the nuts 30. Any water which may be contained within the tube 16 is withdrawn through the drain cock 27, and the valves 24 of one or more of the tubes 17, 18 and 19 are opened to complete the communication between the said compartment of the vessel and the atmosphere above the water level and from the deck of the salvaging vessel. At all times, any desired signal may be transmitted to those within the compartment in the operation of the lights contained within the tube 16 which are visible through the lenses 26 and 50. The use of three lights is merely an element of safety, insuring that at least one of said lights will operate, in the event that two of the lights should become inoperative or burn out for any reason.

For the purpose of illustrating the use of the several tubes 15, 17, 18 and 19, the tube 15 will be regarded as a vent tube, permitting the exhaust of air from the compartment out to atmosphere above the water level, whereas

the tube 17 may be utilized for pumping or supplying fresh air or oxygen to those within the compartment from the suitable apparatus on the salvaging vessel. The tube 18 may be used for the transmission of food products in small packages or carriers of any form to those within the compartment, whereas the tube 19 may be used for any other purpose that may be desired such as for sending tools, 5 implements, electric wires and the like to those in the compartment of the vessel, for example to transmit electric energy for heating electrical apparatus to maintain the desired temperature in said compartment, as 10 15 will be apparent.

It will be understood that the frame consisting of the rings 38 and 41, joined by the arms 39, in addition to maintaining the couplings 43 in unit arrangement, also serves to 20 reinforce and brace said couplings to prevent and obviate breakage thereof when subjected to stress or strain, especially when the apparatus is exposed to heavy seas or rough weather.

With our improved apparatus, it will be 25 apparent that the life of the seamen contained within the compartment in question may be maintained for an indefinite period of time in a very simple, practical and efficient manner. As previously stated, it will be understood that any number of the mechanisms or apparatus herein referred to may be 30 employed for completing a communication with as many compartments of a vessel or ship as desired, as it is often the case that 35 seamen are confined in more than one room or compartment of a vessel. In this way, access to each compartment containing the seamen is made available.

It may be well stated at this time, that one 40 of the tubes or communications may be used for the purpose of pumping out water from a room or compartment should a slight leak of water exist, and on the other hand, the salvaging 45 of the vessel may be facilitated by repairing the exterior of a ship closing a room or compartment to form thereof a float chamber. 50 In this event, however, the diver must first remove the plate 28 opening into such chamber and open the valve 24 of the pipe which is to be used for the purpose stated.

The above described operation which has 55 been applied specifically to the structure shown in Figs. 1 to 5 inclusive, also applies to the structure shown in Fig. 6. It will be understood that while certain details of construction are shown for carrying the invention into effect, our invention is not necessarily limited to these details, and various changes in and modifications of the construction herein shown and described may be made within the scope of the appended 60 claims, without departing from the spirit of

our invention, or sacrificing its advantages.

Having fully described our invention, what we claim as new and desire to secure by Letters Patent, is:

1. The combination with the hull or bulk-head of a vessel, of a passage adapted to place one compartment of a vessel in communication with the exterior of the vessel, the outer end of said passage being contained within the boundaries of the hull, a cover plate normally closing the outer end of said passage, means for closing the inner end of said passage, means involving a flexible tube and a coupling on the end of said tube adapted to be coupled with the ship when said cover has been removed, for placing said flexible tube in communication with said passage, said flexible tube extending to atmosphere whereby when the inner end of said passage is open, devices, elements, and products may be transmitted through said tube and passage into the compartment of the vessel, and means coupled with the exterior of the hull for guiding and reinforcing the flexible tube and the coupling thereof. 70 75 80

2. The combination with the hull or bulk-head of a vessel, of a passage adapted to place one compartment of a vessel in communication with the exterior of the vessel, the outer end of said passage being contained within the boundaries of the hull, a cover plate normally closing the outer end of said passage, means for closing the inner end of said passage, means involving a flexible tube and a coupling on the end of said tube adapted to be coupled with the ship when said cover has been removed, for placing said flexible tube in communication with said passage, said flexible tube extending to atmosphere whereby when the inner end of said passage is open, devices, elements and products may be transmitted through said tube and passage into the compartment of the vessel, means coupled with the exterior of the hull for guiding and reinforcing the flexible tube and the coupling thereof, and another cover plate forming a supplemental closure for the inner end of said passage. 90 95 100 105 110

3. The combination with the hull or bulk-head of a vessel, of a passage adapted to place one compartment of a vessel in communication with the exterior of the vessel, the outer end of said passage being contained within the boundaries of the hull, a cover plate normally closing the outer end of said passage, means for closing the inner end of said passage, means involving a flexible tube and a coupling on the end of said tube adapted to be coupled with the ship when said cover has been removed for placing said flexible tube in communication with said passage, said flexible tube extending to atmosphere whereby when the inner end of said passage is open, devices, elements and products may be transmitted through said tube and pas- 115 120 125 130

sage into the compartment of the vessel, means coupled with the exterior of the hull for guiding and reinforcing the flexible tube and the coupling thereof, another cover plate 5 forming a supplemental closure for the inner end of said passage, and another passage substantially similar to and arranged adjacent said first named passage.

4. An apparatus of the class described comprising means for transmitting devices, products or elements through the hull of a vessel from an exterior source to a compartment within the vessel, comprising a plurality of tubes, a cover for closing the outer end of said tubes, said cover being detachably coupled with the exterior of the hull of the vessel, means for closing the inner ends of said tubes, and a unit involving a plurality of flexible tubes and couplings at the ends of 15 said tubes adapted to be coupled with the respective tubes in said hull when said cover has been removed.

5. An apparatus of the class described comprising means for transmitting devices, products or elements through the hull of a vessel from an exterior source to a compartment within the vessel, comprising a plurality of tubes, a cover for closing the outer end of said tubes, said cover being detachably coupled with the exterior of the hull of the vessel, means for closing the inner ends of said tubes, and a unit involving a plurality of flexible tubes and couplings at the ends of 20 said tubes adapted to be coupled with the respective tubes in said hull when said cover has been removed whereby when the inner ends of said tubes are open, water, food and the like may be transmitted from a source of supply into the compartment of the vessel into which said tubes open.

6. An apparatus of the class described comprising means for transmitting devices, products or elements through the hull of a vessel from an exterior source to a compartment 45 within the vessel, comprising a plurality of tubes, a cover for closing the outer end of said tubes, said cover being detachably coupled with the exterior of the hull of the vessel, means for closing the inner ends of said tubes, a unit involving a plurality of flexible tubes and couplings at the ends of said tubes adapted to be coupled with the respective tubes in said hull when said cover has been removed whereby when the inner ends of said tubes are open, water, food and the like may be transmitted from a source of supply into the compartment of the vessel into which said tubes open, and a supplemental closure 50 for the inner ends of said tubes comprising a cover plate adapted to be removed in completing the communication through said tubes.

7. An apparatus of the class described comprising means for transmitting devices, products or elements through the hull of a

vessel from an exterior source to a compartment within the vessel, comprising a plurality of tubes, a cover for closing the outer end of said tubes, said cover being detachably coupled with the exterior of the hull of the vessel, means for closing the inner ends of said tubes, a unit involving a plurality of flexible tubes and couplings at the ends of said tubes adapted to be coupled with the respective tubes in said hull when said cover has been removed whereby when the inner ends of said tubes are open, water, food and the like may be transmitted from a source of supply into the compartment of the vessel into which said tubes open, a supplemental closure for the inner ends of said tubes comprising a cover plate adapted to be removed in completing the communication through said tubes, and one of said tubes constituting signal transmitting means for transmitting messages from the exterior of the vessel to the said compartment.

8. An apparatus of the class described comprising means for transmitting devices, products or elements through the hull of a vessel from an exterior source to a compartment within the vessel, comprising a plurality of tubes, a cover for closing the outer end of said tubes, said cover being detachably coupled with the exterior of the hull of the vessel, means for closing the inner ends of said tubes, a unit involving a plurality of flexible tubes and couplings at the ends of said tubes adapted to be coupled with the respective tubes in said hull when said cover has been removed whereby when the inner ends of said tubes are open, water, food and the like may be transmitted from a source of supply into the compartment of the vessel into which said tubes open, a supplemental closure for the inner ends of said tubes comprising a cover plate adapted to be removed in completing the communication through said tubes, one of said tubes constituting signal transmitting means for transmitting message from the exterior of the vessel to said compartment, and said unit involving a frame coupled with the exterior of the hull and adapted to guide the couplings of said flexible tubes and to reinforce said couplings and said tubes.

9. In a vessel, the bulkhead of which is provided with a transmitting tube opening outwardly through the bulkhead and inwardly into a compartment within the vessel, a unit comprising a frame, a coupling in said frame and arranged at the end of a flexible tube, said coupling being adapted to place said flexible tube in communication with said transmitting tube, said frame being adapted to be secured to the bulkhead to reinforce said coupling and flexible tube.

10. The combination with the bulkhead of a ship having a plurality of tubes for placing the exterior of the ship in communica-

- tion with a compartment within the ship, of a unit consisting of a plurality of flexible tubes, couplings on the ends of said tubes for placing the flexible tubes in communication with the tubes in said bulkhead, and means for supporting said couplings in predetermined spaced relation to facilitate the alinement and mounting of said couplings in connection with the first named tubes.
11. The combination with the bulkhead of a ship having a plurality of tubes for placing the exterior of the ship in communication with a compartment within the ship, of a unit consisting of a plurality of flexible tubes, couplings on the ends of said tubes for placing the flexible tubes in communication with the tubes in said bulkhead, and means for supporting said couplings in predetermined spaced relation to facilitate the alinement and mounting of said couplings in connection with the first named tubes, said last named means being coupled with the exterior of the bulkhead and also serving to reinforce said couplings and said flexible tubes.
12. A vessel, the hull of which is provided with a passage formed by part of the hull structure and adapted to place one compartment of a vessel in communication with the exterior of the vessel, the outer end of said passage being contained within the boundaries of the hull, the outer end of the passage being open, a cover plate coupled with the hull and normally closing the outer end of said passage, means for closing the inner end of the passage within the hull, and said closure means involving a lens.
13. A vessel, the hull of which is provided with a plurality of independent passages adapted to place the interior of the hull in communication with the exterior thereof, inner and outer closure plates attached to the hull for closing said passages, and manually operated means exposed to the interior of the hull structure when the inner cover plate is removed for opening and closing said passages.

In testimony that we claim the foregoing as our invention we have signed our names this 10th day of February, 1928.

CHARLES A. OHMAN.
